CLAIM

The ornamental design for a light fixture as shown and described.

DESCRIPTION

FIG. 1 is a perspective view of a light fixture showing our new design;

FIG. 2 is a front view of the claimed design shown in FIG. 1;

FIG. 3 is a rear view of the claimed design shown in FIG. 1;

FIG. 4 is a side view of the claimed design shown in FIG. 1;

FIG. 5 is another side view of the claimed design shown in FIG. 1;

FIG. 6 is a top view of the claimed design shown in FIG. 1; and,

FIG. 7 is a bottom view of the claimed design shown in FIG. 1.

The broken lines in the drawings show unclaimed portions of the light fixture and form no part of the claimed design. Break lines having a jagged edge appear in the length of the light fixture. The appearance of any portion of the light fixture between the break lines forms no part of the claimed design.
